UNITED STATES PATENT OFFICE.

JOSEPH ROBINSON, OF NEW YORK, N. Y.

AUTOMATIC TRAIN-PIPE COUPLING.

Application filed July 1, 1921, Serial No. 481,967. Renewed November 23, 1925.

This invention relates to automatic train pipe couplings—and particularly to that type in which a spring is threaded through the supporting bracket to permit adjustment of the coupling head toward or from the bracket. It has been found difficult and expensive to thread the bracket so as to adjustably receive the spring, this because the dimensions of both the bracket casting and the spring vary considerably in process of manufacture. High production, and hence economical production, of these parts can be had only by eliminating the need for hand fitting them. It is the object of the present invention to attain this advantage.

My invention resides in the combinations, arrangements, and constructions hereinafter described, pointed out in the appended claims, and illustrated in the accompanying drawings in which:

Figure 1 is a side elevation of my improvement.

Figure 2 is a rear view of Figure 1 with the coupling head omitted.

Figure 3 is a vertical section through the lower end of the bracket with some of the parts omitted.

Figure 4 is a horizontal sectional view through the lower end of the bracket and the chamber therein. In this view some of the parts are omitted.

Figure 5 is a sectional plan view of a modification of my improvement, and

Figure 6 is a rear view thereof.

Having reference to the drawings. My improvement comprises a bracket A having a chamber or opening 5 in its lower end in which is adjustably mounted the rear end of a coiled supporting spring. The spring extends through the opening or chamber and for a short distance to the rear of the bracket

8. Within the opening or chamber 5, and nearer the rear side of the bracket than the front side thereof, I provide an inwardly extending flange or projection 6 formed integral with one wall of the chamber and inscribing about one half the interior circumference of the chamber. The flange preferably extends inwardly at a right angle to the wall of the chamber and is shaped to follow and conform substantially to the pitch of the coils of the spring B. The thickness of the flange is considerably less than the space between the coils of the spring, while the inside diameter of the chamber 5 is considerably greater than the inside diameter of the

spring B. This arrangement facilitates manufacture and insures that the spring will always enter the chamber, the spring being rotated upon engagement with the flange 6 to 60 permit the flange to enter the space between the spring coils and travel along such coils as the spring is rotated in or screwed through the bracket A. As appears in Figures 3 and 4 the flange 6 constitutes an abutment for the 65 spring B, and since it is located near the rear side of the bracket the maximum number of free coils between the flange and the coupling head is obtained, thus permitting greater resiliency and life to the spring. As aforesaid 70 the fit between the spring and chamber 5 is preferably a loose fit to simplify manufacturing and facilitate interchangeability of these parts.

To clamp or lock the spring in the chamber, and in the desired position, I provide a clamp member 7 having on its inner face a groove or recess 8 shaped to fit and receive that portion of the spring coil which is opposite the portion engaged by the flange, the ring 80 being provided with a toe 9 which is hooked through an opening 10 formed in the bracket at one side of the chamber 5 and in alignment with a semi-circumferential slot 11 which extends through the wall of the chamber opposite the flange 6. At one end of the slot, and on the lower side of the chamber I provide a lug or ear 12, and through this, and through a similar ear 13 on the clamp 7 I pass a bolt, or other suitable locking device 90 14 which serves to draw the clamp 7 tightly against the spring B and force the latter against the opposite inner wall of the chamber 5 thus rigidly locking the spring against undesired movement in the chamber. It will 95 be observed that the clamp 7 occupies the slot 11, and co-operates with the flange 6 to form an abutment for the spring B.

Any desired type of coupling head C may be carried by my improved support and may be connected to the forward end of the spring B in any desired manner. I preferably provide a laterally diverging conduit 15 to which the head is threadingly connected and I provide the conduit on its rear side with an annular seat 16 upon which is mounted the forward end of the spring B. To lock this end of spring on this seat I provide the conduit 15 with a stem 17 which extends rearwardly from the seat 16 through the spring B and the chamber 5. Upon the rear end of this stem I threadingly mount a nut 18 having a

weighted handle 19 to maintain the nut in the adjusted position. Between the nut and the rear end of the spring B I provide a plate 20 shaped to properly receive the end coil of the spring. By drawing upon the nut 18, through the medium of its handle 19, the spring B is placed under compression against the seat 16. This compression is preferably sufficient to prevent the coupling head C from 10 rotating out of position about the forward end of the spring.

When it is desired to adjust the coupling head toward or from the bracket A, the tension of the spring against the seat 16 is relieved by backing off the nut 18, whereupon the bolt 14 is loosened and the spring B is rotated in the desired direction in the chamber 5 and about the seat 16. This rotation of the spring will cause it to move forward or backward in the chamber, the flange 6 and the clamp 7 following the coils as the spring is thus moved. When the adjustment desired is obtained, which may be any extent from a fraction of an inch to the full length of 25 the spring, the nut 18 is turned up until the desired pressure of the spring is again had on the seat 16. The bolt 14 is then tightened thus, drawing the clamp 7 firmly against the spring and rigidly clamping the latter in 30 the adjusted position. This construction provides a simple and efficient support which is economical to manufacture, easy to assemble, and dependable in operation. Any suitable train pipe hose may, of course, be connected to the conduit 15 in the usual way, while the bracket A is attached to the ordinary car coupler lug 21 as by bolts 22, and may have more than one flange 6 if desired.

In Figures 5 and 6 I illustrate a modification 40 of my improvement in which the chamber 5 of the bracket A is provided at one side with a laterally extended elongated perforated portion 23 through which is passed a T shaped steel anchor device D comprising 45 a head 24 and a stem 25. The head 24 is provided with grooves or recesses 26 adapted to receive one or more of the coils of the spring B. The stem or shank 25 extends across the opening in the chamber 5 and between the coils of the spring B as shown. At the opposite side of the chamber 5 the stem passes through a sleeve 27 formed integral with the chamber 5. A washer or abutment 28 is rigidly connected with the stem 55 25 and between it and the bottom of the sleeve 27 a coiled spring 29 is placed. A nut 30 having a weighted handle 31 is threaded to the outer end of the stem 25 and serves to draw the anchor device D into tight engagement with the spring B and force the spring firmly against the inner side of the chamber 5 opposite the elongated portion 23. Contact between the head 24 of the anchor device D, and the inner walls of the portion 23, 60 firmly locks the spring B against longitudinal

movement in the chamber 5, as shown at 32 in Figure 5. When it is desired to adjust the spring B, with this modification of my improvement, the nut 30 is relieved by rotating it through the medium of the handle 31, 70 whereupon the locking device D is urged out of the locked position by the tension of the spring 29, thus releasing the spring B and permitting the same to be rotated and adjusted in the chamber 5, the spring B being 75 caused to move forward or backward in the chamber 5 upon such rotation inasmuch as the coils of the spring are in effect threadingly connected with the locking device D, through the medium of the head 24 and the 80 grooves 26 formed therein. The reverse of this operation firmly locks the spring in the service position. This arrangement comprehends screw means engaging the spring B at one side thereof to adjustably lock the 85 spring in the chamber 5.

The present invention is an improvement over the construction shown in my Patent Number 1,666,310 for an improvement in automatic train pipe couplings granted Apr. 17, 90 1928, the spring B of such construction may, of course, be adjustably mounted in the collar 11 thereof in the manner herein described, if desired.

What I claim is:

1. In an automatic train pipe connector, a coupling head, a bracket having a horizontally arranged cylindrical chamber rigid therewith, a coiled spring extending from said head rearwardly through said chamber, 100 said chamber having on one side a vertically arranged slot extending through the wall thereof, a curved clamping member arranged in said slot, said clamping member being anchored at its upper end to said bracket, and means at the lower end of said member for drawing the same into said slot and against said spring, whereby the spring is clamped in said chamber.

2. In an automatic train pipe connector, a coupling head, a bracket having a horizontally arranged cylindrical chamber at its lower end rigid therewith, a coiled spring extending from said head rearwardly through said chamber, said chamber on one side having a vertically arranged slot extending through the wall thereof, a clamping member mounted in said slot, said clamping member having a rib on its inner face adapted to fit between the coils of said spring, said chamber opposite said clamping member also having a rib adapted to fit between the coils of said spring, said clamping member at its upper end being pivotally associated with said bracket, and means engaging the lower end of said member for forcing the same into said slot whereby said spring is clamped in said chamber with said ribs lying between the coils of the spring.

3. In an automatic train pipe connector, a

coupling head, a bracket having a horizontally arranged cylindrical chamber at its lower end rigid therewith, a coiled spring extending from said head rearwardly through 5 said chamber, said chamber having in one side wall thereof a vertically arranged slot, a clamping member mounted in said slot, said clamping member being anchored to said

bracket above said chamber, and means engaging said bracket and said clamping member below said chamber for forcing 10 said member into said slot and against said spring.

In testimony whereof I affix my signature.

JOSEPH ROBINSON.
